UNITED STATES PATENT OFFICE.

MICHAEL FALOS, OF BOSTON, MASSACHUSETTS.

TOOL-HANDLE.

1,391,726.

Specification of Letters Patent. Patented Sept. 27, 1921.

Application filed June 11, 1920. Serial No. 388,160.

To all whom it may concern:

Be it known that I, MICHAEL FALOS, a citizen of Ukraine, residing at Boston, in the county of Suffolk and State of Massachusetts, have invented certain new and useful Improvements in Tool-Handles, of which the following is a specification.

The present invention relates to certain new and useful improvements in a tool handle wherein devices are adapted for attachment to the handle for supporting either a saw, file or other tools.

With the above and other objects in view, the present invention consists in the novel form, combination and arrangement of parts hereinafter more fully described and shown in the accompanying drawings, wherein like reference characters indicate similar parts throughout the several views.

20 In the drawings,

Figure 1 is a side elevational view partially in section of the handle having a file blade supported therein,

Fig. 2 is a top plan view of the same with 25 the file blade broken away,

Fig. 3 is a side elevational view of a modified form of file support with the handle broken away,

Fig. 4 is a side elevational view of the 30 saw blade support with the handle partially broken away,

Fig. 5 is a cross sectional view taken on line V—V of Fig. 1 showing the clamping bars for engaging the inner end of the file 35 blade,

Fig. 6 is a cross sectional view taken on line VI—VI of Fig. 1,

Figs. 7 and 8 are detail perspective views 40 of the clamping bars carried by the handle for engaging the file blade, and

Fig. 9 is a perspective view of the block for supporting the free end of the file blade.

Referring more in detail to the accompanying drawings, there is illustrated a 45 combined file and saw handle embodying an arched portion 1 provided with finger and hand braces 2 and 3, the forward end of the handle portion 1 being of increased cross sectional area to provide a block 4 while the 50 rear end of the handle 1 is channel-shaped as at 5 and formed cylindrical at the extreme end thereof as at 6 for the passage of supporting devices for the saw and file blades.

55 One type of device for supporting the inner end of the file blade is shown in Figs.

1, 5, 7, and 8 and embodies a rod 7 of tapering rectangular formation to fit within the channel portion 5 of the handle 1 and carrying a screw extension 8 for passage through the circular end 6 of the handle to receive the adjusting nut 9 as shown in Fig. 1. The outer end of the rod 7 carries a right angularly extending depending head 10, the inner face of which is recessed and stepped as 65 at 11 while upper and lower bolt receiving openings 12 are provided therein. A clamping plate 13 co-operates with the head and is provided with a recess 14 in one face thereof co-operating with the stepped recess 11. 70 Threaded openings 15 are provided in the upper and lower ends of the plate 13 and are adapted for alignment with the openings 12 in the head 10 while thumb screws 16 freely pass through the head openings 12 and 75 thread into the screw openings 15 to vary the distance between the side walls of the recessed portions 11 and 14. A file blade 17 has the inner tapered mounting ends 18 thereof disposed in the opposed recessed portions 11 and 14 while an adjustment of the thumb screws 16 clamps the saw blade in position.

The bearing block is provided for the outer end of the handle 1 in engagement with the 85 saw blade 17 and is shown in detail in Figs. 1, 6 and 9. The block 19 carries a screw 20 freely projecting through the opening 21 in the handle block 4 with a thumb nut 22 threaded upon the inner end thereof for 90 clamping the block in the desired position with the lower end of the block engaging the upper face of the file blade 17. The handle 1 may be gripped as desired, and the file blade reciprocated thereby while the 95 block 14 engaging the upper face of the blade will determine the pressure thereon. The clamping heads hold the file blade adjustably mounted in the handle while the file blade supporting bar 7 is removably mounted with- 100 in the handle end 6.

A modified form of file mount is shown in Fig. 3 and embodies an arm 23 having a mounting screw 8' with an adjusting nut 9' therefor while the forward end thereof is 105 provided with a socket 24 for the reception of the inner end 18 of the file blade 17, a set screw 25 passing through the side wall of the socket 24 for engagement with the file blade to hold the same in position. The 110 forward end of the blade 17 passes through the opening 26 in the lower end of the block

19 while the screw 20 upon the block retains the same in position in the enlarged head 4 of the handle frame 1.

A saw support is shown in Fig. 4 wherein 5 an angle bracket 27 carries a screw 8" passing through the end 6 of the handle part 1 and retained in position by the thumb nut 9". An angle bracket 28 carries a screw 10 extension 29 passing through the head 4 of the handle 1 and is retained in the handle by the thumb nut 30. The saw blade 31 is connected at one of its ends to the lower 15 end of the bracket 27 as indicated at 32 while the other end of the saw blade 31 is secured as at 33 to a mount 34, which mount carries an angle bar 35 freely projecting through an opening 36 in the depending arm of the bracket 28 while a screw 37 carried by the mount freely projects through the 20 lower end of the bracket arm 28 and is retained therein by the thumb nut 38.

It will therefore be seen that with the provision of a single supporting handle 1, modified forms of brackets may be provided 25 therefor for supporting file blades and saw blades, and while there are herein shown and described the preferred embodiments of the invention, it is nevertheless to be understood that minor changes may be made there- 30 in without departing from the spirit and scope of the same.

What is claimed as new is:

1. An implement of the class described comprising an arched handle, an apertured 35 head carried by one end thereof, the opposite end of said handle having a passage opening therein, tool supports associated with each end of the handle, one of said supports including a block, a screw carried 40 by the block and extending through the head of the handle and an adjusting nut for said screw.

2. An implement of the class described comprising an arched handle, an apertured 45 head carried by one end thereof, the opposite

end of said handle having a passage opening therein, tool supports associated with each end of the handle, one of said supports including a rod having a screw extension projecting through the passage opening in the 50 handle and an adjusting nut for the projecting screw.

3. An implement of the class described comprising an arched handle, an apertured head carried by one end thereof, the opposite 55 end of said handle having a passage opening therein, tool supports associated with each end of the handle, one of said supports including a rod having a screw extension projecting through the passage opening in the 60 handle, an adjusting nut for the projecting screw, and a clamping head carried by said rod.

4. An implement of the class described comprising an arched handle, an apertured 65 head carried by one end thereof, the opposite end of said handle having a passage opening therein, tool supports associated with each 70 end of the handle, one of said supports including a rod having a screw extension projecting through the passage opening in the handle, an adjusting nut for the projecting screw, an angularly disposed head carried by said rod and a plate clamped to said head.

5. An implement of the type described 75 comprising a handle of arched formation, a tool supporting bracket removably attached to each end of the handle, and terminal and intermediate hand grips projecting laterally 80 of the arched portion of the handle.

6. An implement of the type described comprising a handle of arched formation having one end extended to provide a hand grip, brackets carried by the handle adapted to support a tool in operative position relative thereto, and additional hand grips carried by the arched portion of the handle and projecting laterally thereof.

In testimony whereof I affix my signature.
MICHAEL FALOS.
